UNITED STATES PATENT OFFICE

GARNET P. GRANT, OF LONG ISLAND CITY, NEW YORK, ASSIGNOR TO AUTOSALES CORPORATION, OF LONG ISLAND CITY, NEW YORK, A CORPORATION OF NEW YORK

DESIGN FOR A VENDING-MACHINE CABINET

Application filed January 10, 1930. Serial No. 34,091. Term of patent 3½ years.

To all whom it may concern:

Be it known that I, GARNET P. GRANT, a subject of the King of England, residing at Long Island City, in the county of Queens and State of New York, have invented a new, original, and ornamental Design for a Vending-Machine Cabinet, of which the following is a specification, reference being had to the accompanying drawing, forming part hereof.

The figure is a front perspective view of a vending machine cabinet, showing my new design.

I claim:

The ornamental design for a vending machine cabinet, as shown.

GARNET P. GRANT.
